M. SIMON

Des. 163,336

PLAQUE OR SIMILAR ARTICLE

Filed April 3, 1948

FIG. 1

FIG. 2

INVENTOR

Maurice Simon

UNITED STATES PATENT OFFICE

163,336

PLAQUE OR SIMILAR ARTICLE

Maurice Simon, St. Louis, Mo.

Application April 3, 1948, Serial No. 145,513

Term of patent 14 years

(Cl. D29—2)

To all whom it may concern:

Be it known that I, Maurice Simon, a citizen of the United States, residing in the city of St. Louis and State of Missouri, have invented a new, original, and ornamental Design for Plaque or Similar Article, of which the following is a specification, reference being had to the accompanying drawing, forming part thereof.

In the drawing, Fig. 1 is a front elevation view of a plaque or similar article, showing my new design. Fig. 2 is a top edge view thereof.

I claim:

The ornamental design for a plaque or similar article, as shown.

MAURICE SIMON.
